THERMOSTATIC SWITCH

Noble G. Brumgart, Mattoon, Ill.

Application July 3, 1940, Serial No. 343,856

1 Claim. (Cl. 200—137)

The present invention relates to new and useful improvements in switches and more particularly to a thermostatic switch adapted to be used in conjunction with the journal boxes of railway rolling stock with the principal object in view to warn trainmen of "hot boxes" as they occur by proper indication inside of the rolling stock.

Another object of the invention is to provide a switch of the character stated which can be installed in the journal boxes of railway rolling stock without any likelihood of the same interfering with the proper functioning of the box.

Still another important object of the invention is to provide a switch of the character stated which will be positive acting and not susceptible to the ready development of defects.

In the drawing:

Figure 1 represents a side elevational view of the switch shown in upright position and mounted in a journal box.

Figure 2 is a vertical sectional view taken substantially on the line 2—2 of Figure 1.

Figure 3 is a horizontal sectional view on the line 3—3 of Figure 2.

Figure 4 is a top plan view of the switch.

Figure 5 is a diagrammatic view disclosing the electrical connections between the electrical devices involved.

Referring to the drawing wherein like numerals designate like parts, it can be seen that A generally refers to a railroad rolling stock journal box, while B generally refers to the thermostatic switch, the upper end of which is disposed through the top of the journal box and held by suitable brackets 3—3. Thus the switch is held in a vertical position with the thermostatic element thereof, immediately opposed to the corresponding journal. Numeral 5 denotes an elongated trough-like structure preferably of brass or other metal having the side walls 6, bottom wall 7, end walls 8 and 9. Disposed in this trough-like structure, which is open on one side is the thermostatic element generally referred to by numeral 10. This thermostatic element consists of a plurality of U-shaped elements, the present invention as illustrated being disclosed with three of these U-shaped elements, the intermediate element having the end of its leg portion connected to the end portions of the opposed legs of the adjacent U-shaped element. Obviously, more than three of these U-shaped elements may be employed if seen fit. Obviously, this thermostatic unit 10 will expand under heat in the trough-like structure 5.

One end leg of the unit 10 is connected by a bolt 11 having a nut 12, extending through a threaded bushing 13 in the bottom wall 9. The other end leg of the unit 10 normally bears against the push rod 14 which is slidably dis-

posed through a guide structure or protuberance in the upper wall 8 defining a threaded nipple 15.

The outer end of this push rod 14 has the bridge member 16 thereon and a coiled spring 17 is located on this rod 14 between the upper end leg of the thermostatic unit and the aforementioned nipple 15 for the purpose of maintaining the rod urged downwardly and against the said leg at the upper end of the thermostatic unit. 10 In this manner, the bridge member 16 is held spaced from the contacts 18 which are located on pins 19 extending through bushings 20 of insulation in the end wall 21 of a cap 22, which is threadedly engaged over the nipple 15.

Obviously, this switch can be mounted in any suitable manner in a packing box, or in face elsewhere and a socket type plug can be engaged over the prongs 19 for connecting the switch with a source of current 23 and suitable indicating lamps 24, which, of course, can be annunciators if desired and in the case of rolling stock, for indicating hot boxes, there will preferably be two of these lamps 24 at each end of a car and perhaps one for each journal box.

25 Obviously, when the thermostatic element 10 expands under undue heating conditions, the bridge member 16 bridges the contacts 18 and current flows from the battery 23 to the lamps 24 or to a buzzer or other warning signal, if desired.

30 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

35 A switch of the character described comprising a trough-like structure having side walls, a bottom wall and end walls, one end wall provided with a removable plug therein, the other end wall being provided with a threaded extension, an internally threaded cap for disposition over the extension, a contact in the cap, said extension and adjacent end wall of the trough-like structure being formed with a bore, a push rod slidably disposed through the bore and having a head engageable with the contact when forced in the direction of the cap, a longitudinally expandable thermostatic element disposed in the trough-like structure and having one end attached to the plug, said plug being adjustably disposed in its end wall, and spring means on the push rod normally tending to urge the push rod against the adjacent end of the thermostatic element.

NOBLE G. BRUMGART.
